Primary Examiner—Wallace R. Burke*Assistant Examiner*—H. Baynham*Attorney, Agent, or Firm*—Victor Flores[57] **CLAIM**

The ornamental design for a water pipe, as shown and described.

DESCRIPTION

FIG. 1 is a perspective view of a water pipe, showing my design;

FIG. 2 is a front elevational view thereof;

FIG. 3 is a right side elevational view thereof with the opposite side being a mirror image thereof; and,

FIG. 4 is a top plan view thereof.

The undisclosed bottom plan view is planar and unornamented.

FIG. 1

FIG. 4

FIG. 2

FIG. 3
